U.S. CL. 84—397

10 Claims

ABSTRACT OF THE DISCLOSURE

A fluid release valve for brass wind instruments (cornets, trumpets, trombones and the like) commonly known as a water key but distinct and different from the conventional pivoted lever-type water key. It comprises a valve body embodying a cylinder and an enclosed spring-loaded piston which reciprocates in the cylinder and which simultaneously opens and closes diametrically opposite fluid inlet and discharge ports and has a push-button-type finger-piece at a readily accessible end of the valve body.

This invention relates to water keys such as are currently provided on brass wind instruments such as cornets, trumpets, flugelhorns, trombones, baritones, tubas and the like and has to do, more particularly, with an adaptation which is characterized by a fixed cylinder having inlet and discharge ports and a spring-biased piston-type valve which is finger actuated and effectually serves the purposes for which it has been devised.

The ambient temperature of the area in which a brass wind instrument is usually played is almost invariably lower than the temperature of the moving air column which is blown into and through the tubing. The resultant condensate and moisture if permitted to accumulate, may gurgle and otherwise impair the performance and capability of the instrument. To cope with this problem, instrument manufacturers provide each instrument with a pivoted lever-type spring-closed water key of well known construction.

Knowledgeable and precision minded brass instrument players have repeatedly called attention to seemingly small but significant mechanical defects known to exist, for example, in high velocity instruments, such as cornets and trumpets. The water key now being used has been found to be lacking in efficiency in that the relatively large fluid pooling release tap constitutes a void which noticeably disturbs the instrument's intonation and tonal center and impedes the desired smooth flow of air. In fact, it is common knowledge that recognized artists have their instruments made minus the conventional water key and bodily remove the required slide or crook in a manner to drain and dispose of unwanted fluid. To the ends desired, the herein disclosed piston valve has a sleeve-like body which can be soldered or otherwise fixed in requisite close proximity to the coacting wall of the tubing, thus placing the discharge port distal to the seal. It follows that the void is reduced as much as 80%, whereby to permit uninhibited flow of the column of air.

Failure of the coil spring in the regular lever-type water key is also a potential difficulty. The fact is, the spring is known to be under optimum torsion in order to keep the pad seated and sealed and accordingly increases to maximum tensional strain when the lever is manually tripped. Manifestly, breakage of the spring or loss of the seal while playing renders the instrument useless until the required repair can be made.

Another aspect of the instant concept has to do with weight and appearance. In carrying out the principles of the present invention these factors have been accorded consideration with the result that in the improved water

2

valve or key the weight has been reduced to as much as 2 to 5 grams less than that of presently used water keys. Then, too, the design of the improved water key dispenses with cumbersome and detracting appearance factors and also reduces the number of parts to a minimum and thus saves time, labor and assembling expense. A further feature of the specially designed appearance of the device ties in with effective elimination of a separate seal, and more significantly, minimizes operational movement by approximately 75% compared to the movement required in actuation of the aforementioned conventional water key.

Briefly the herein disclosed improved water key lends itself to feasible and effectual use on the regularly used tubing of the instrument. However, and as will be hereinafter noted, the water release port is of a depth and diameter significantly less than the depth and diameter of the regularly used port. The valve body takes the form of an elongated sleeve with an internal cylindrical bore which defines the desired cylinder. Readily applicable and removable means functions to close one end of the sleeve. The other end of the sleeve has a wall provided with an axial guide opening. A first median wall portion of the sleeve has an inlet port of predetermined diameter which corresponds to the small diameter water release port in the tubing. A second median portion of the sleeve diametrically opposite the inlet port has a discharge or emptying port. A leak-proof piston of requisite length and diameter is precision-fitted and reciprocable in the cylinder and has one end portion fashioned to firmly abut the inner portion of the surface of the apertured end of the sleeve. The main body portion of the piston normally and simultaneously covers and closes both inlet and discharge ports. An end of the body portion of the piston has an axial socket to accommodate an end portion of a coil spring which is confined in the cylinder and has one end retentively fitted into the socket and its other end in end thrust abutting as well as operative and coacting contact with the aforementioned closure means. That end portion of the piston, which can perhaps be described as a shank, projects outwardly and slidably through an opening provided therefor and provides a push button.

The push button can be a solid type snugly but slidably fitted into the guide opening. Alternatively, it can be in the form of a cup or cap which is slidably capped over an end portion of the sleeve to provide an adequate operating push button.

In carrying out the principles of the invention the spring utilized is of a requisite coiled type. It can be and is under minimum tension when in its normal port closing position. Only enough tension is required to keep the piston seal covering the inlet and discharge ports in the valve body. Repeated experimental use of a valve devised and constructed as herein shown and described has shown that the spring-loaded piston well serves the purposes for which it has been perfected and that the spring will outlast torsion springs such as are used as a component part of the aforementioned lever-type water key.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a fragmentary perspective view showing the aforementioned tubing, for example, tubing such as is employed in a trumpet, and illustrating, what is more significant, the improved piston and cylinder type valve or water key and how it is mounted and intended for use.

FIG. 2 is an enlarged fragmentary view with parts in section and elevation and emphasizing the construction and coaction of the component parts.

FIG. 3 is an enlarged view with parts in section and elevation showing the improved water key or valve with the body or main part of the piston covering and blocking both inlet and discharge ports, and

FIG. 4 is a view similar to FIG. 3 showing a modification such as will be hereinafter fully described.

By way of introduction to the description of the details it may well be pointed out that both embodiments of the water key or valve are structurally and functionally similar. However it seems advisable to describe these embodiments separately. With this in mind the overall tubing of the aforementioned instrument is denoted in FIG. 1 by the numeral 6. That part of the tubing which is primarily under consideration herein is denoted by the numeral 8 and as shown in FIG. 2 the tubing wall is usually .020 thick. The diameter of the release orifice or port 10 (FIG. 2) is .100 and the depth is 0.30.

The self-contained ready-to-use water key or valve is denoted, generally stated, by the numeral 12. The valve body 14 is of elongated sleeve form and the attachable median portion is provided with a segmental recess 16 which is conformingly fitted and soldered in place as at 18. The bore of the body is of uniform diameter from end to end and provides the aforementioned cylinder 20. One end wall of the body, the wall 22, is provided with a guide opening 24 of requisite diameter. The other end portion of the body (at the left in FIG. 3) that is, the end portion 26 is open and provided inwardly of the terminal end with an endless groove 28 to accommodate a split ring 30 which is seated and held in place in the manner shown. This arrangement serves to accommodate an insertable and removable disk-like member 32 which provides a closure, and which is held in the cylinder by the split ring and which has an axial boss 34 which serves in the manner shown. The inlet orifice or port in the upper median portion of the sleeve is denoted by the numeral 36 and corresponds in diameter with the release port 10. It is diametrically opposite the exit or discharge port 38. If desired the bottom portion is recessed as at 40 to accommodate a coacting part of an optionally useable discharge nipple 42.

A valve body serves to accommodate the manually actuatable spring-loaded or spring-biased piston valve. This piston or valve comprises a main body portion 44 which has an axial recess 46 therein. This recess serves to accommodate end coils of a suitably tensioned coil spring 48. The other end coils are positioned in thrust relation with the end closing disk 32 and are arranged to encompass the piloting and retaining boss 34. The right hand portion of the piston, which comprises a disk-like head, is denoted at 50 and is of a diameter to effectively close the guide opening 24. The median part of the piston is provided with an encompassing annular groove or channel 52 and which constitutes a fluid by-passing or clearance channel. This channel is normally in the valve closing position, shown in FIG. 3. Obviously it can be pushed from right to left to assume a port opening position. This head 50 is centrally provided with an integral extension or projection 54 which extends outwardly through and beyond the opening 24 and provides a finger-actuable push button. Normally the push button is in the ready-to-use position shown in FIGS. 1 and 3. By exerting pressure against the button and the tension of the spring 48 the piston valve 44 can be moved from the normal closing position to the left in FIG. 3, whereupon the channel or encircling groove lines up with the ports 10, 36 and 38 to make for requisite drainage of liquid or moisture as the case may be.

With respect to the slight modification shown in FIG. 4 the instrument tubing is here referred to by the numeral 60, the release orifice or port being denoted at 62. This port is in line with the inlet port 64 in the median part of the sleeve-like valve body 66. The port 64 corresponds in diameter with the port 62 and also is of the same diameter as the discharge port 66 in the bottom intermediate

or median portion of the valve body. The arcuate or segmental seat 68 is conformingly fitted against the periphery of the tubing and is welded or otherwise secured in place as at 70. The left hand open end of the valve body is internally screw-threaded, the end portion being denoted at 72. The threads serve to accommodate suitable threads 74 on the neck of a closing cover or closure 76. The periphery of this can be knurled if desired (not detailed). This closure is located at one end of the cylinder 78, the other end wall of the valve body, denoted at 80, is provided with a guide hole 82.

The piston valve has a body portion 84 which is fittingly arranged in the cylinder to simultaneously close the inlet and discharge ports 64 and 66. Here again an axial socket 86 is provided to accommodate the end coils of the coil spring 88. The left hand end 87 of the coil spring is seated in a pocket provided therefor in the closure 76. The encircling peripheral or surface groove or channel 90 is here slightly different from that shown at 52 in FIG. 3. However the function is the same. Likewise the abutment head 92 here abuts the apertured end wall but is slightly different in that it is provided with a screw-threaded shank 94 which extends through the guide opening and is screwed into an axial socket member 96 forming an integral part of the push button cap. The cap is denoted at 98 and has an encircling flange 100 which is slidingly and fittingly capped over the coacting end portion of the valve body. The discharge nipple here is denoted at 102 and is soldered or otherwise fixed to line up with the discharge port 66. The manner in which this embodiment of the invention is mounted and functions is believed to be clear from the views of the drawing.

Experience has shown that the invention disclosed, compared to prior art adaptations, is characterized by fewer parts. There are no rubber or cork seals required. In fact, less pressure is required to achieve the normal valve closing action. Further one solder connection to the instrument instead of several is significant. In addition the invention is simple, practical and is easier to maintain. Although light and durable it is amply sturdy to achieve the precision action and end results desired.

It may and should be explained that the desired leak prevention result is not dependent on either of the spring retaining sleeve-closing members 32 or 76 nor the apertured ends 22 or 80 (FIGS. 3 and 4 respectively). The tolerance between the I.D. of the valve body 14 and the O.D. of the pistons 44 and 50 provides the closure or seal against air leak. This is accomplished by centerless grinding the piston body .0002 undersize in relation to the precision reamed valve body.

It is believed that a careful study of the views in connection with the specification will enable the reader to obtain a clear and comprehensive understanding of the invention and features and advantages and manner of use. A more extended description is deemed to be unnecessary.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

65 What is claimed as new is as follows:

1. In a brass musical instrument embodying a length of tubing having a water release port, a normally closed water valve for opening and closing said port at will, said valve comprising a hollow valve body fixed on an exterior surface of said tubing, and having an inlet orifice proximal to and cooperatively aligned with said water key port and also having a distal discharge port for draining said body, and a readily accessible valve member operatively mounted in said valve body adapted to simultaneously open and close both said inlet orifice and said

discharge port, said valve member in the closed position lying substantially flush with said surface of said tubing.

2. The combination defined in and according to claim 1, and wherein said inlet orifice and discharge port are diametrically opposite each other.

3. The combination defined in and according to claim 1 and wherein said body has an internal cylindrical bore, said valve member comprising a plunger, said plunger embodying a cylindrical piston fitting slidably in said bore and normally spanning and closing both said inlet orifice and discharge port.

4. The combination defined in and according to claim 1, and wherein said body comprises an elongated sleeve having an internal cylindrical bore, a cylindrical spring-biased piston fitting slidably in said bore and having operating means at one readily accessible end of the sleeve adapted to be manually actuated in a manner to open and close said orifice and said discharge port at will.

5. The combination defined in and according to claim 4, and wherein said one end is provided with an axial guide opening, that portion of the piston which is adjacent to and cooperable with said one end having means slidable through and outwardly beyond said one end and provided with a button-like finger actuated member providing the aforementioned operating means.

6. The combination defined in and according to claim 5, and wherein said sleeve is provided at its other end with manually applicable and removable closure means which when removed enables one to have access to said bore, spring and piston.

7. A water key for a brass wind instrument which embodies tubing provided with a water release port comprising an elongated sleeve having an internal cylindrical bore, readily applicable and removable closure means covering and closing one end of said sleeve, the other end of said sleeve having an axial guide opening, a first median wall portion of said sleeve having an inlet port of predetermined diameter corresponding to the diameter of said water release port, a second median portion of said sleeve diametrically opposite said inlet port having a discharge port, a piston reciprocable in said cylinder

and having one end abutting an inner surface of said other end of said sleeve, said piston being reciprocable in said cylinder and normally simultaneously covering and closing both said inlet and discharge ports, said piston in the closed position lying substantially flush with said water release port, said piston having an axial socket, a coil spring confined in said cylinder and having one end retentively fitting into said socket and its other end abutting and operatively and retentively coacting with said closure means, and said one end having an outwardly disposed side provided with finger actuated operating means.

8. The water key defined in and according to claim 7, and wherein the median peripheral surface portion of said piston is encircled by a circumferential fluid bypassing and clearance groove which is adapted to be simultaneously registered with said inlet and discharge ports when the valve is intentionally opened for drainage needs.

9. The water key defined in and according to claim 8, and wherein said finger actuated operating means comprises a readily accessible push-button.

10. The water key defined in and according to claim 8, and wherein said finger actuated operating means comprises a readily accessible cap which is guidingly and slidingly capped over a coacting end of said sleeve and provides a conveniently accessible push-button.
